CLAIM

The ornamental design for a cryotherapy activator station, as shown and described.

DESCRIPTION

FIG. 1 is a perspective view of a cryotherapy activator station in accordance with the present invention;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof;

FIG. 7 is a bottom plan view thereof; and,

FIG. 8 is another perspective view thereof with a tweezer seated therein.

The portions of the cryotherapy activator station shown in broken lines form no part of the claimed design. The tweezer seated in the cryotherapy activator station, as illustrated in FIG. 8, is shown in broken lines and forms no part of the claimed design.

1 Claim, 8 Drawing Sheets
